UNITED STATES PATENT OFFICE

ELOF L. CARLSON, OF BRISTOL, CONNECTICUT, ASSIGNOR TO THE E. INGRAHAM CO.,
OF BRISTOL, CONNECTICUT, A CORPORATION

ALARM CLOCK

Application filed May 31, 1929. Serial No. 367,187.

This invention relates to improvement in alarm clocks and particularly to the means employed for manually shutting off the alarm after the same has been automatically sounded.

The object of this invention is to provide a simple and reliable manually-operable shut-off mechanism for alarm clocks constructed with particular reference to capacity for ready assembly and dis-assembly to facilitate the inspection, adjustment and repair of the clock.

With the above object in view, my invention consists in an alarm clock having certain details of construction and combinations of parts as will be hereinafter described and particularly recited in the claims.

In the accompanying drawings:

Fig. 1 is a face view of an alarm clock embodying my invention;

Fig. 2 is a broken view partly in front elevation and partly in vertical section;

Fig. 3 is a transverse sectional view taken on the line 3—3 of Fig. 2;

Fig. 4 is a similar view but showing the pendant-head unscrewed and inclined to align the grooved lower end of the shut-off plunger with the large end of the key-hole slot in the shut-off slide;

Fig. 5 is a detached perspective view of the shut-off slide; and

Fig. 6 is a corresponding view of the shut-off plunger.

In carrying out my invention as herein shown, I employ a reciprocating shut-off plunger 10 mounted for vertical movement in an axial guide-passage 11 in a pendant-head 12 having a depending externally-threaded tubular stem 13 extending through the periphery of the clock-case 14 and into an internally-threaded bushing 15 riveted into the periphery of the case-back 16. An inverted cup-shaped sheet-metal washer 17 is interposed between the inner face of the pendant-head 12 and the periphery of the clock-case 14.

The pendant-head 12 before referred to is provided with the usual pivotal pendant-bow 18 and by means of its externally-threaded stem 13 serves to couple the clock-

case 14 and case-back 16 together against axial separation.

The shut-off plunger 10 is provided at its upper end with a ball-like finger-button 19 and near its pointed inner end 20 is provided with an annular groove 21 adapted to be hooked into engagement with the opposite walls of the contracted portion 22 of a key-hole slot 23. The said key-hole slot 23 terminates at its rear end in the usual enlarged circular portion 24 and is formed in the horizontally-extending arm 25 of a reciprocating sheet-metal shut-off slide 26.

The shut-off slide just above referred to is formed with an inwardly-offsetting bowed shut-off finger 27 adapted to engage the teeth of a verge-wheel 28 forming a usual feature of an alarm-train which requires no detailed description herein, other than to say that it includes the usual verge 29 having secured to it a hammer-arm 30 carrying at its outer end a hammer 31 adapted to oscillate back and forth to strike a bell 32 through a clearance-opening 33 formed in the periphery of the case-back 16.

The shut-off slide 26 is mounted for vertical movement against the rear face of the front movement-plate 34 by means of a stud 35 which is riveted into the said front movement-plate 34 and mounts a spring-washer 36 which yieldingly holds the said slide 26 against the rear face of the movement-plate 34. The stud 35 extends through a slot 37 in the shut-off slide 26 which latter is also formed with a clearance-slot 38 through which the alarm-set stem 39 passes and with a forwardly-bent guide-finger 40 reciprocating in a slot 41 formed in the movement-plate 34 aforesaid.

From the foregoing it will be seen that the shut-off slide 26 may be lowered or raised by the shut-off plunger 10 to move the shut-off finger 27 into and out of engagement with the teeth of the verge-wheel 28 so as to respectively stop and release the alarm-train.

If for any reason it should be desired to axially separate the clock-case 14 and case-back 16 the pendant-head 12 will be rotated so as to unscrew its stem 13 from the bushing 15 and permit the said head together with

the shut-off plunger, to be rocked into the position shown in Fig. 4 so as to align its grooved lower end with the enlarged portion 24 of the key-hole slot 23 and permit the removal as a unit of the said head, pendant-bow 5 18 and shut-off plunger 10.

When it is desired to reinstall the unit comprising the pendant-head pendant-bow and shut-off plunger in the clock, the process 10 described in the preceding paragraph for its removal, will be reversed, the pointed end 20 facilitating at this time, the re-hooking of the plunger into the key-hole slot 23.

While I have shown and described the 15 preferred embodiment of my invention as employing a grooved plunger and a shut-off slide provided with a key-hole slot, it is obvious without detailed description that other means of connecting the plunger and 20 slide or their equivalents may be employed, so long as the means is of such hooked character as to be disengageable when the guide-fixture and plunger are tilted after unfastening the said guide-fixture.

25 I claim:

1. In an alarm clock, the combination with a manually-operable alarm shut-off plunger formed with an annular coupling-groove; of a guide-fixture therefor removably fastened 30 to the clock-structure so as to be tilttable with respect thereto when unfastened; and an alarm-shut-off member positioned within the clock-case and formed with a key-hole slot having its enlarged portion located out of 35 line with the normal path of movement of the said plunger and adapted to receive the grooved portion of the same; whereby when the said guide-fixture is unfastened the same may be tilted to align the grooved inner end 40 of the shut-off plunger with the enlarged portion of the said key-hole slot to disconnect the said plunger from the shut-off member.

2. An alarm clock as defined in claim 1 45 and having the guide-fixture threaded into an opening in the clock-structure which is larger in diameter than the diameter of the said plunger to permit the tilting of the said guide and plunger as a unit to disengage the latter from the alarm-shut-off member within 50 the clock-case.

3. In an alarm clock, the combination with a manually-operable alarm-shut-off plunger formed with an annular coupling-groove; 55 of a guide-fixture for the said plunger removably fastened to the clock-structure so as to be tilttable with respect thereto when unfastened; a vertically-reciprocatable alarm-shut-off member having a horizontal arm 60 formed with a key-hole slot having its enlarged portion located out of line with the normal path of movement of the said plunger and adapted to receive the grooved portion 65 of the same; whereby when the said guide-fixture is unfastened the same may be tilted to

align the grooved inner end of the shut-off plunger with the enlarged portion of the said key-hole slot to disconnect the said plunger from the said horizontal arm of the shut-off member.

4. In an alarm clock, the combination with

a clock-case and a case-back; of a guide-fixture passing through the periphery of the said clock-case and threaded into the periphery of the said case-back; a manually-operable alarm-shut-off plunger mounted in the said guide-fixture and formed with an annular coupling-groove; and an alarm-shut-off member positioned within the clock-case and formed with a key-hole slot having its enlarged portion located out of line with the normal path of movement of the said plunger and adapted to receive the grooved portion of the same; whereby when the said guide-fixture is unscrewed the same may be tilted to align the grooved inner end of the shut-off plunger with the enlarged portion of the said key-hole slot to disconnect the said plunger from the shut-off member.

5. In an alarm clock, the combination with

a clock-case and a case-back; an internally-threaded bushing secured in the periphery of the said case-back; a guide-fixture having a tubular externally-threaded stem extending through the periphery of the clock-case and threaded into the said bushing; a manually-operable alarm-shut-off plunger formed with an annular coupling-groove and axially reciprocatable in the said guide-fixture and its stem; an alarm-shut-off member positioned within the clock-case and formed with a key-hole slot having its enlarged portion located out of line with the normal path of movement of the said plunger and adapted to receive the grooved portion of the same; whereby when the said guide-fixture is unscrewed the same may be tilted to align the grooved inner end of the shut-off plunger with the enlarged portion of the said key-hole slot to disconnect the said plunger from the shut-off member.

6. In an alarm clock, the combination with

a manually-operable alarm-shut-off plunger; of a clock-housing formed with an opening larger in diameter than the diameter of the said plunger and through which the said plunger passes; a plunger-guide removably mounted in the clock-housing in line with the said opening therein; an alarm-shut-off member located within the said housing; and hooked connection between the said plunger and alarm-shut-off member constructed and arranged to be released when the said plunger is tilted out of its normal position by the disconnection of the said guide-fixture from the said housing.

In testimony whereof, I have signed this specification.

ELOF L. CARLSON.
